CLAIM

The ornamental design for an outboard cowling, as shown and described.

DESCRIPTION

FIG. 1 is a perspective view of an outboard cowling in accordance with the present invention.

FIG. 2 is a right side view of the outboard cowling shown in FIG. 1, the left side view being a mirror image thereof.

FIG. 3 is a rear view of the outboard cowling shown in FIG. 1.

FIG. 4 is a front view of the outboard cowling shown in FIG. 1; and,

FIG. 5 is a top view of the outboard cowling shown in FIG. 1.
